GARMENT PLACKET

Eugene Pedatella, New York, N. Y.

Application May 18, 1942, Serial No. 443,346

2 Claims. (Cl. 2—74)

This invention relates generally to placket openings for garments, but more specifically to means for closing such openings by application of cooperating tape members to the placket edges.

The main object of the invention resides in the provision of cooperating tape members adapted to be secured to placket edges of a garment, the said tape members carrying non-metallic engageable elements to effectuate a concealed closure for the placket opening.

A further object of the invention resides in the provision of concealed non-metallic closure means for placket openings in garments which lends flexibility in all directions in this region of the garment, which is non-corrosive to perspiration and to cleaning and washing fluids, which is economical to apply, efficient in operation and flat in appearance.

These objects and other incidental ends and advantages of the invention will hereinafter appear in the progress of the disclosure and as pointed out in the appended claims.

Accompanying this specification is a drawing showing a preferred embodiment of the invention wherein corresponding reference characters designate corresponding parts throughout the several views, and wherein:

Figure 1 is a front view in perspective showing the closure means applied to a placket opening of a dress.

Figure 2 is a front view in perspective showing similar closure means applied to a placket opening of a skirt.

Figure 3 is a partial front view in elevation showing the closure means applied to the placket edges of the dress of Figure 1, the said view having portions broken away.

Figure 4 is a sectional view of Figure 3 through the plane 4—4 thereof.

Dress A shown in Figure 1 is provided with a conventional placket opening C at the waist portion formed between panels 10 and 14, the overlapping placket edges being designated by numerals 10a and 14a respectively. Secured to the underside of placket edge 10a, as by line of stitching 12, is a longitudinal strip member 11 of any suitable non-metallic material such as cloth, canvas, goods of the same material as the dress, or the like, having a series of spaced engaging members such as buttonholes 13 running along the length thereof.

Strip member 11 is adapted to be engaged between the inner faces of opposite similar superposing strip members 15 and 16 joined at the outer edges to the underside of panel 14, as by a line of stitching 17, the forward edge of the upper strip 16 also being secured to the underside of panel 14 adjacent placket edge 14a as by a line

of stitching 18. Lower strip 15 is provided with a series of spaced cooperating engaging members such as non-metallic buttons 19 to register with buttonholes 13.

In this manner, upper strip 16 serves as a covering wall for the engagement of strip 11 with strip 15 by detachable fastening means comprising buttonholes 13 and buttons 19. The strips 11, 15 and 16 at the upper and lower edges are secured to panels 10 and 14 by common lines of transverse stitching such as 20 and 21, the said stitching being disposed above and below the placket opening C.

The invention above described is applicable to garments wherein the placket opening proceeds from the waistband of a garment downwardly as in the case of a skirt shown in Figure 2. Where applied to the placket of a skirt, strip 11 is free at the upper transverse edge and forms a continuation with the upper edge of the waistband 22, but strips 15 and 16 may be secured together by a transverse line of stitching 21a through the upper edge of the waistband portion opposite strip 11.

By the use of engageable strip members with non-metallic fastening means as described, a placket closure for conventional placket edges is attained which is flat, neat, economical to apply, flexible, non-corrosive and concealed, and may be applicable to any type of garment.

I wish it understood that minor changes and variations in the material, location, integration and size of parts used, may all be resorted to without departing from the spirit of the invention and the scope of the appended claims.

I claim:

1. In a placket opening for a garment, a longitudinal strip member projecting from and secured to one placket edge, a pair of opposite, superposing and similar strip members extending inwardly from the other placket edge and engaging the first mentioned strip member both being secured to the garment at the edges distant from the other placket edge, and one of the pair of the strip members being secured to and adjacent the said other placket edge.

2. In a placket opening for a garment, a longitudinal strip member projecting from and secured on one placket edge, a pair of opposite, superposing and similar strip members extending inwardly from the other placket edge and engaging the first mentioned strip member both being secured to the garment at the edges distant from the other placket edge and one of the pair of the strip members being secured to and adjacent the said other placket edge, cooperating members between said strip members for detachable fastening thereof.

EUGENE PEDATELLA.
